PROCESS OF RECOVERING HYDROCARBON OILS AND OTHER BYPRODUCTS FROM OIL SHALE AND THE LIKE

Elmer H. Records and James E. Louttit, Tacoma,
Wash.; said Louttit assignor to said Records

Application October 18, 1937, Serial No. 169,594

8 Claims. (Cl. 202—15)

This invention deals with the art of recovering hydrocarbon oils and other valuable byproducts from oil shale, bituminous sands and like raw materials, and it has reference more particularly to a novel process utilizing superheated steam solely as the heating medium and wherein vital chemical reactions are brought about by the addition to the shale, sands or other material under distillation, of certain solid, liquid or gaseous materials that are high in hydrocarbons of a desired nature, whereby to increase the yield of hydrocarbon oils and low boiling oils of value; it being the principal object of this invention to provide a process that is an improvement upon the generally used recovering processes and which leads to the recovery of a greater quantity and a superior quality of products and byproducts than heretofore has been possible.

Explanatory to the present invention, it will here be stated that the organic matter that makes up the hydrocarbon oils in oil shale are classified as pyrobitumens, and these, upon destructive distillation, yield oils of various character which have been termed "Kerogen" or "green oil." Kerogen, as such, has a large and complex molecule, which, of itself, has little practical value. The present process, or treatment, utilizing comparatively low pressures and moderate heat, has for an object and provides for the recovery of these oils in a cured or refined condition. At the same time, the reaction is supplied with vital and necessary compounds so that reformation in a single operation increases the yield of valuable hydrocarbon oils and the production of the same with a large volume of low boiling oil of extreme value as motor fuel.

This reaction is a simultaneous decomposition of the complex kerogen molecule and a polymerization of products of such decomposition to reform as a large volume of saturated naphtha and paraffin molecules of both closed and open chain types. This is made possible by the use of coal, lignite or similar volatile carbonaceous substances so placed in the reaction chamber that the evolving volatiles contact the destructively distilled oil shale simultaneously; coal, lignite and such hydrocarbons being used because they supply a continuous flow of such evolving vapors and require approximately the same length of time for destructive distillation as is required by the oil shale.

The destructive distillation of the coal or lignite in the base of the retort results in a considerable evolution of gases containing hydrogen. This hydrogen, upon combining with the de-

composed kerogen, results in a high degree of saturation of the resulting compounds.

In accordance with the present process, superheated steam at temperatures ranging from 700° F. to 1800° F. and at pressures from atmospheric to fifty pounds is used. Under the conditions of this process, the superheated steam as the sole heating medium is desirable because of its high specific heat and active hydrogen and oxygen content with the absence of inert gases, and another advantage in its use is that heat carried into the mass by the superheated steam is uniformly distributed, and although the temperatures are controlled so that decomposition of the shale takes place, there are no hot walls or zones of sufficient temperature to allow cracking of the final vaporous products formed in the final reaction. This has resulted in a material decrease in the length of time of treatment encountered in other methods or processes. Furthermore, it has been found that the increased yield of hydrocarbon oil is due to the enriching effect of the reactions of the process and that such oils are much easier refined and a decrease in refinery losses results therefrom.

In the accompanying drawing, there is illustrated diagrammatically an improved apparatus for carrying out the present process, and in this drawing, 1 designates, in the entirety, the reaction retort; 2, a condenser; 3, a decanter; and 4, the steam superheater. The reaction retort 1 comprises a cylindrical vessel preferably built of steel boiler plate and comprising an outer shell 10 and an inner shell 11 of lesser diameter. These are coaxially disposed, to provide an intermediate, annular space or expansion chamber 16, and at their lower ends are welded together as at 5 to form a gas-tight joint and are drawn inwardly to form a throat leading to an outlet or opening 12 of restricted diameter. On the inside face of the inner shell 11 at the beginning of the throat or restricted portion, vertically spaced baffle rings 13 and 14 are welded within the shell. The lower edges of these baffles are spaced from the walls of the shell for the purpose of deflecting the discharging residue toward the axial center, and also to serve as protective guards overlying a plurality of ports 15 which open through the shell 11 from the intermediate space 16, or expansion chamber, into the reaction chamber.

At its upper end, the edge of the shell 10 is turned inwardly and is welded to the inner shell to form a steam and gas-tight connection therewith, and there are one or more pipes 17 lead-

ing from the superheater 4 into the upper end of the expansion chamber 16, and the flow of steam through each pipe is controlled by a valve as designated at 18.

Fitted over the upper end of the shell 11, which extends somewhat above the shell 10 and expansion chamber 16, is a closure or lid 19 which is seated in a gas-tight joint, and is normally held clamped in place by a cross clamp bar 20 and a jack screw 21 mounted on the bar to engage the lid.

Upon removal of the lid, the reaction chamber is opened for charging, and this may be done by means of a bucket as designated at 23. A pipe 22 leads horizontally from the upper end 15 of the reaction chamber through the side of the enclosing shell and near the top, and this opens into the condenser 2 and is used to conduct the final vapors and gases and spent steam from the reaction chamber into the condenser. At its inner end, the pipe 22 terminates near or at the center of the reaction chamber, and is provided at that end with a T-fitting 24, having the cross head portion disposed in a vertical plane. The upper end of the cross head is closed by means of a plug 25 while the lower end is open. A pressure tank 26 is arranged somewhat above the reaction chamber to contain a supply of oil which may be conducted through a pipe 27 into the reaction chamber to the fitting 24, 30 and is then conducted downward through a pipe 28 to cause the oil to spray into the mass being treated slightly above the coal or lignite zone. Suitable supports or brackets 29 may be utilized to brace and support the lower end of the pipe 28.

It is preferred that the entire reaction chamber be covered with a suitable insulation 30 of the spun slag type. The reaction chamber proper will be supported by the columns 31 and the brick work 32, and material discharged from the reaction chamber, through the opening 12 at the lower end thereof falls into a quench chamber D. The opening 12 is provided with a gas-tight discharge door 33 which may be manually or mechanically moved in guideways in a horizontal frame 34 into and from closed position. In the present instance, the door is shown as being equipped with a handle 35 for this purpose.

Operating along the floor of this quench chamber D is a conveyer 36 of apron or chain type, which is used to carry off the discharged and spent shale and coal to the waste dump. This conveyer may be made to serve one or more reaction chambers placed in a row if occasion arises.

Assuming the reaction chamber to be so constructed, and the parts arranged as illustrated, the method of use and operation, briefly described, is as follows:

First, the charging lid 19 is removed and the reaction chamber is first charged with spent or broken raw shale in an amount sufficient to cover the baffles 13, thus filling the lower end zone which is designated within the bracket C. Over this zone C, the required amount of coal or lignite is charged to fill the zone designated within the bracket B. Then broken oil shale is charged into the main part of the reaction chamber to near the upper end, thus filling the zone designated within the bracket A. The 70 charging thus being completed, the lid 14 is clamped in place and tightened with the bar and jack screw provided.

In the meantime, superheated steam has been provided in superheater 4 at the temperatures 75

and pressures required. Valve 18 is then opened, allowing the superheated steam to pass into the expansion chamber 16 and through the apertures 15 into the bottom of the reaction chamber and into the charge that is to be treated. Upon passing upward through the charge, the superheated steam starts decomposition of the coal and shale, losing a considerable portion of its specific heat in the process. As the volatiles contained in the coal rise through the shale mass, they, in combination with other released gases from the steam and shale, reform into hydrocarbon molecules of gaseous and liquid nature. These are thoroughly mixed by turbulence in the upper portion of the reaction chamber, and pass out through the T-fitting 24, pipe 22 and valve 31, which has been opened, and enter the condenser 2 which may be of an air cooled or water cooled type.

The condensed hydrocarbons and steam then pass through a seal pipe 39 leading from the lower end of the condenser into the decanting vessel 3. The hydrocarbon oils of this process, being lighter than water, break away from the water or condensed steam in the decanter and rise to the top of the vessel, as indicated, there to be drawn off through a pipe 40 and conducted thereby to proper storage tanks. A pipe 41 leading from the decanter at a lower level than the pipe 40 is used to maintain a desired water level. The noncondensable gases formed are of high B. t. u. content and pass from the condenser into proper gas holders through a pipe 38.

At proper intervals, oily hydrocarbons stored in the pressure tank 26 may, upon opening a valve 27 on pipe 27, be injected under pressure into the distilling mass through pipes 27 and 28. This period of treatment varies with the type of oil shale used, but it has been found that this process will take considerably less time of reaction than that required by processes that resort to external heating methods. Upon completion of the proper treatment, then the valve 35 or valves 18 are closed, as is also the valve 37. The discharge trap 33 is then opened and the shale in the bottom of the retort, in zone C, the carbonized coal in zone B, together with the spent shale in zone A, will then fall by gravity into the chamber D and into the conveyer 36 and may be carried thereby to waste.

In drawing the charge, it is desirable, however, to leave enough of the spent shale of zone A in the reaction chamber to form a base or zone C for the next charge which is cycled in a manner similar to that described above.

In the use of super-heated steam, it has been found that low steam pressures are an advantage and that they can be varied from atmospheric to twenty-five pounds for general use, although for certain types of oil shales, it may be desirable to use pressures somewhat higher. Temperatures of the incoming steam for general operation will be approximately 1200° F., but it has been found that in order to take advantage of the exothermic and endothermic cycles of the reacting mass, that temperatures from 700° to 1800° F. may be necessary. In no case should the temperature be so great that secondary reactions predominate.

It has been found by the present method of processing that a much larger proportion of paraffin hydrocarbons are formed having the general formula C_2H_{2n+2} ; such paraffins being of the open chain or saturated type. It has al-

so been found that there is a higher proportion of saturated monocyclic or naphthalene series of compounds of the general formula C_nH_{2n} ; these being of ring or closed chain type.

These types of saturated compounds are very desirable as they are easily converted into motor fuel of high anti-knock rating as well as a lubricating oil and wax of value. The yield of such motor fuel is thus greater than that ordinarily obtained from oil shale by simple destructive distillation.

The foregoing description is intended to be illustrative of the process and of an apparatus for practising it, and it is not intended that it shall in any way be restrictive, but that the invention described shall be liberally construed in accordance with the claims appended hereto, and in construing these claims it is desired that the word "coal" shall apply equally to coal, lignite or other carbonaceous materials capable of the same results, while "oil-shale" shall be understood to be any of the various oil-shales, bituminous sands and like raw materials capable of the uses herein explained in connection with this process.

Having thus described our invention, what we claim as new therein and desire to secure by Letters Patent is:

1. The process of recovering hydrocarbon oils and gases from oil-shale which comprises enclosing a mass of oil-shale in a reaction retort upon a base of coal, then passing superheated steam through the coal and oil-shale to effect decomposition thereof and in a manner whereby the decomposition products from the coal pass through the mass of oil-shale and finally withdrawing and condensing the said products.

2. The process of recovering hydrocarbon oils and gases from oil-shale which comprises enclosing a mass of oil-shale in a reaction retort upon a base of coal, then passing superheated steam at a temperature of not less than 700° F. and pressure of not over fifty pounds through the coal and oil-shale to effect decomposition thereof and in a manner whereby the decomposition products from the coal pass through the mass of oil-shale and finally withdrawing and condensing the said products.

3. The process of recovering hydrocarbon oils and gases from oil-shale comprising enclosing a mass of oil-shale in a reaction retort upon a layer of coal, passing superheated steam upwardly through the coal and oil-shale to effect decom-

position thereof and injecting a low boiling hydrocarbon oil into the mass of shale oil intermittently as decomposition and polymerization proceeds, and drawing off and condensing the products of distillation.

4. The process of recovering hydrocarbon oils from oil-shale comprising enclosing a mass of oil-shale in a closed reaction retort upon a base layer of coal, heating the coal and oil-shale with a stream of superheated steam passed upwardly therethrough and mixing the evolved vapors in a space in the reaction retort above the mass of shale, then withdrawing and condensing the vapors.

5. The process of producing combustible gas comprising enclosing a mass of oil-shale and a quantity of coal in a closed reaction chamber, introducing superheated steam as a reaction medium, and causing the evolved gases to mix without cracking.

6. The process of producing hydrocarbon oils and gases from oil-shale, comprising simultaneously decomposing oil-shale and coal in a closed reaction chamber by the use of superheated steam as the heating medium and recombining the molecules of the hydrocarbon vapors so formed by the enrichening and saturating gases and vapors of the distilled coal.

7. A process of producing hydrocarbon oils and gases from oil-shale by subdividing a small layer of coal or lignite in such a manner that decomposition products from such coal pass upward through a mass of oil-shale in a closed reaction chamber; passing superheated steam through the coal and shale as the sole reducing medium, said superheated steam to be not less than 700° F and at a pressure not over 50 pounds; and spraying volatile hydrocarbon oil into a reaction zone in the lower part of said oil-shale in such a manner that the uprising superheated steam will react upon such liquid hydrocarbon and that the gases so formed may rise and combine with the volatile products of the decomposing oil-shale and coal.

8. A process which comprises the decomposition of a mass of oil-shale and a thin bed of coal or lignite, and a small stream of a volatile hydrocarbon liquid, and the recombining in a heated reaction medium of superheated steam at not over 50 pounds pressure and a temperature over 700° F.
